(57) **CLAIM**

The ornamental design for a glove, as shown and described.

DESCRIPTION

FIG. 1 is a front view of the glove;

FIG. 2 is a rear view thereof;

FIG. 3 is a left view thereof;

FIG. 4 is a right view thereof;

FIG. 5 is a plan view thereof;

FIG. 6 is a bottom view thereof;

FIG. 7 is a perspective view thereof; and,

FIG. 8 is another perspective view thereof.

The broken lines showing of wrist portions of the glove and the broken lines adjacent to the solid claimed lines on the fingers of the glove which define the bounds of the claimed design are for illustrative purposes only and forms no part of the claimed design.
